Atty's.

UNITED STATES PATENT OFFICE

CLAYTON L. DAY, OF NEW YORK, N. Y., ASSIGNOR TO CHICAGO BRIDGE & IRON CO., A CORPORATION OF ILLINOIS

CONTAINER FOR VOLATILE LIQUIDS

Application filed December 21, 1927. Serial No. 241,603.

This invention relates to improvements in containers for volatile liquids, and more especially to such a container adapted to hold internal gas pressure in order to prevent vapor losses.

Containers of the type referred to are preferably provided with a more or less flattened roof on a cylindrical shell. When the container is so designed, it is contemplated that 10 the total upward gas pressure against the roof tending to draw up on the side wall and force the bottom into spherical shape will be balanced to some extent by the weight of liquid in the tank. In a container of this kind, 15 there must be some means for venting the pressure in the tank in the event the liquid level reaches a predetermined minimum height.

One of the features of my invention is the 20 provision of simple automatic means for relieving the gas pressure in the event the liquid level is lower than the level necessary to balance the internal pressure against the roof.

Other features and advantages of my invention will appear more fully as I proceed 25 with my specification.

In that form of device embodying my invention shown in the accompanying drawings, Figure 1 is a vertical sectional view taken as 30 indicated by the line 1 of Fig. 2, and Fig. 2 is a top plan view.

As shown in the drawings, the tank or container may include the well known cylindrical shell 10 with the bottom 11 and the standard 35 dome roof 12 designed for internal pressure. 13 indicates liquid in the tank, and in a design of this kind the weight of said liquid is utilized to counterbalance the upward gas pressure against the roof 12. 13^a indicates the 40 minimum height of liquid required to balance the predetermined gas pressure.

In a tank of this kind, therefore, there must be some means for venting the internal pressure in event the liquid level drops below that 45 indicated by 13^a. This is accomplished by providing a vent pipe 14 extending above the roof 12 as indicated by 14^a to give the liquid gas pressure. In other words, the head of liquid in the pipe 14 will determine the internal gas pressure to be held. The lower end

of the pipe 14 as indicated by 14^b is at the same height as the minimum liquid level indicated by 13^a, so that if the liquid drops below this level, the head of liquid in the pipe will be lost and the gas pressure vented. 55

The automatic venting means shown is a very simple attachment and eliminates the necessity of anchoring the shell at its base to prevent its assuming a tendency toward sphericity or providing other means for counterbalancing the upward gas pressure against the roof 12. 60

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty 65 in my invention as broadly as possible in view of the prior art. 70

What I claim is new, and desire to secure by Letters Patent, is:

1. In combination with a closed container 75 for volatile liquids with internal gas pressure, having a substantially flat bottom constructed of sheet material subject to distortion by excessive internal gas pressure in the container if not held down by a certain amount of liquid, means for automatically venting the internal gas pressure upon the liquid dropping to a predetermined level, said means comprising a vent pipe with its lower end in the container at substantially the minimum height of the liquid at which the pressure is to be vented, and its upper end outside of the container. 80

2. In combination with a closed container 85 for volatile liquids with internal gas pressure, having a substantially flat bottom constructed of sheet material subject to distortion by excessive internal gas pressure in the container if not held down by a certain amount of liquid, means for automatically venting the internal gas pressure upon the liquid dropping to a predetermined level, said means comprising a vent pipe with its lower end in the container at substantially the minimum height of the liquid at which the pressure is 90

100

to be vented, and its upper end outside of the container at a sufficient height to maintain the desired internal pressure when the lower end of the vent pipe is immersed in the liquid.

5 In witness whereof, I have hereunto set my hand this 12th day of December, 1927.

CLAYTON L. DAY.
